CLAIM

The ornamental design for an adjustable seat for a bench, as shown.

DESCRIPTION

FIG. 1 is a perspective view of an adjustable seat for a bench showing a first embodiment of our new design in an environment.

FIG. 2 is a front perspective view of the adjustable seat for a bench of FIG. 1.

FIG. 3 is a rear perspective view of the adjustable seat for a bench of FIG. 1.

FIG. 4 is a front elevation view of the adjustable seat for a bench of FIG. 1.

FIG. 5 is a rear elevation view of the adjustable seat for a bench of FIG. 1.

FIG. 6 is a right elevation view of the adjustable seat for a bench of FIG. 1.

FIG. 7 is a left elevation view of the adjustable seat for a bench of FIG. 1.

FIG. 8 is a top plan view of the adjustable seat for a bench of FIG. 1.

FIG. 9 is a bottom plan view of the adjustable seat for a bench of FIG. 1.

FIG. 10 is a perspective view of an adjustable seat for a bench showing a second embodiment of our new design in an environment.

FIG. 11 is a front perspective view of the adjustable seat for a bench of FIG. 10.

FIG. 12 is a rear perspective view of the adjustable seat for a bench of FIG. 10.

FIG. 13 is a front elevation view of the adjustable seat for a bench of FIG. 10.

FIG. 14 is a rear elevation view of the adjustable seat for a bench of FIG. 10.

FIG. 15 is a right elevation view of the adjustable seat for a bench of FIG. 10.

FIG. 16 is a left elevation view of the adjustable seat for a bench of FIG. 10.

FIG. 17 is a top plan view of the adjustable seat for a bench of FIG. 10; and,

FIG. 18 is a bottom plan view of the adjustable seat for a bench of FIG. 10.

The broken lines in FIGS. 2-9 and 11-18 illustrate portions of the adjustable seat for a bench that form no part of the claimed design. The additional broken lines in FIGS. 1 and 10 illustrate environmental subject matter and form no part of the claimed design.
